UNITED STATES PATENT OFFICE.

WILLIAM D. HEER, OF CHICAGO, ILLINOIS.

COIN-WRAPPING MACHINE.

1,287,303.

Specification of Letters Patent. Patented Dec. 10, 1918.

Application filed October 29, 1917. Serial No. 198,917.

To all whom it may concern:

Be it known that I, WILLIAM D. HEER, a citizen of the United States, residing at Chicago, in the county of Cook and State 5 of Illinois, have invented certain new and useful Improvements in Coin-Wrapping Machines, of which the following is a specification.

This invention relates to coin wrapping 10 machines, and has among its more important objects to provide a device in which a number of coins can be held in a holder preparatory to being wrapped; to produce a construction in which the coins can be packed 15 aged in a rapid manner; to provide a construction which holds a stack or row of coins so that they may be packaged without the danger of any of the coins becoming displaced from the row; to produce a device 20 vice that holds the stack of coins in proper position upon the paper wrapper so that the coins may be easily packaged; to provide a mechanism which is adjustable for various diameters of coins; to provide a device that 25 can be adjusted for different lengths of coin stacks due to the varying width of different coins; to provide a simple adjusting mechanism for the above adjustments; to produce a compact device, simple in construction, 30 strong in its various parts, and one that can be manufactured at a minimum cost, and in general to provide a superior and improved device of the character described.

35 The invention consists of the above matters and others hereinafter described and more particularly pointed out in the appended claims.

In the drawings:

40 Figure 1 is a plan view.
Fig. 2 is a section on line 2—2 of Fig. 1.
Fig. 3 is a central longitudinal section.
Fig. 4 is a section on line 4—4 of Fig. 1.
Fig. 5 is a detail of the paper guide, and 45 Fig. 6 is a view of the pin adjustment indicator.

Referring to the drawings 11 is a base or frame of box-like construction the top of which is at an incline due to the fact that 50 the left hand end of the device, as looked at in Fig. 3 is shorter than the other end. This base 11 has a partition 12 parallel with the table upon which the device is adapted to stand. A roller supporting bracket 55 13 is secured at one end to the partition 12 by a screw 14 and at the other end to the

top plate of the frame 15 by a pair of screws 16. The vertical part of this bracket is provided with a pair of openings 17 in which are adapted to freely rotate a pair of rollers 60 18 and 19, the other ends of the rollers are secured in the vertical front wall of the frame. The top plate 15 of the base 11 is provided with a narrow elongated slot 21.

Upon the upper rear portion of the frame 65 11 is mounted a casing 22 substantially square in plan. This casing has its lower side portions bent at right angles furnishing two extension pieces 23 and 25, the extension piece 25 having a bent end portion 70 25¹ adapted to enter a slot 25² in the top 15 of the frame 11, the other piece 23 has one bent portion 23¹ projecting into slot 23². The extension 23 is provided with a slot 24 through which projects a screw 26 in the 75 top plate 15. The arrangements permit the casing to slide upon this screw and be located and held in any desired position on the frame 15. Projecting forwardly from the front edge of the extension piece 23 is 80 a paper holding finger 27. The casing may be swung upon the pivot 25¹—25² by loosening the screw 26.

Within the casing is mounted what is termed the pin adjusting mechanism, this 85 consists of a bracket 28 secured at one end to the top of the casing by means of screws 29. The other end of this bracket projects downwardly and rearwardly (as viewed in Fig. 3) and on the lower end thereof is slidably mounted a block 29, having rack teeth 31. A bracket 32 is rigidly secured in the block 29 and has on its lower end a pin or plug 33. Mounted transversely of the casing 22 is a pin 34 having a thumb nut 35 95 on one end, and has its other end projecting into the side of the casing 22. Midway between the ends on this pin is fixed a pinion 36 designed to mesh with the rack teeth 31.

A paper guide 37, shown separately in 100 Fig. 5 has a slot 38 which is designed to surround the pin 34. The guide is held on pin 34 by frictional fit between the wall of the casing and the enlarged part 39 of the pin 34. The lower end 41 of the paper 105 guide projects downward through the opening 21 in the top plate 15 and lies under the pin 33. The sheet of paper 40 is held down against the rollers 18 and 19 by the end 41 of the paper guide, and also by finger 27.

The casing 22 is longitudinally adjustable

and, as previously stated, can be secured in any desired position on the frame by means of a screw 26. A guide scale 43 is provided so as to indicate the position to secure the 5 casing when the proper number of any given denomination of coin is to be wrapped. The paper wrapper, which is of standard size and markings for each denomination of coin, is placed on the top plate with one side 10 flush with the front wall of the casing 22. The slide case 22 and paper wrapper 40 are now moved to the proper position, such position being determined by the markings 43. This scale is so graduated that when 15 the case 22 is adjusted for say the standard package of nickels as shown in Fig. 3 the outer end of the stack lies flush with the forward end of the frame 11. In conjunction with this adjustment is another ad- 20 justment, the purpose of which is to move the pin 33 so that it will be in the center of the coin of whatever denomination is to be packaged. For this purpose an indicator scale 45 shown separately in Fig. 6 is pro- 25 vided. If the relative thickness and diameter of coins remained the same for the various denominations only one adjustment would be necessary but the pin adjustment which moves the pin up and down for dif- 30 ferent diameters of coins, also moves for-ward and backward at the same time. Both these movements are uniform, hence the slide case adjustment becomes necessary.

When a stack of nickels (20) is to be 35 wrapped the standard nickel wrapper is selected and placed in the device with one edge adjacent the casing 22. Then the pin adjustment and casing adjustment are made for nickels. The pin adjustment places the 40 center of the pin in the center of the stack of nickels. If the pin were too high or too low the stack of nickels might slip out of place because of the incline of the top plate. This incline causes the coin stack to remain 45 in contact with the pin. The pin adjustment also leaves the proper space between either end of the stack and the edge of the paper. The purpose of this is to have the printing on the wrapper come in the proper place on 50 the package when wrapped and also to have a sufficient margin of paper left to properly cover the end of the package when wrapped.

The casing adjustment is important in that an accurate and rapid check can be had on the number of coins about to be wrapped, 55 if twenty-one are in the stack the slide casing adjustment will cause the last one in the stack to fall off the device, if only nineteen are in the stack, a space will be left at the end of the row for an additional nickel, 60 this shortage is quickly noticed by the operator.

The roll of coins lies on the rollers 18 and 19 with the lower end thereof abutting the pin 33. The paper 40 as shown in Fig. 2 65 is held so that the left hand end can be grasped. The paper is then turned up and over the top of the stack of coins, the stack of coins is now rolled around on the rollers and the paper gradually pulled up until the 70 coins are completely wrapped. The ends of the paper are now turned in and pressed down.

While I have shown and described details 75 of construction to more readily explain my device I do not wish to be limited to such details, but the scope of the invention should be determined by the claims.

I claim:

1. In a coin wrapping device, a main 80 frame, a casing on said frame, a pin in said casing, and a single mechanism for moving said pin vertically and horizontally.

2. In a device for packaging coins, a 85 frame, coin supporting rollers journaled in said frame, a longitudinally adjustable sliding guide case mounted upon said frame, means for securing said case in various positions on said frame, a coin positioning pin mounted in guide case and above the rollers, 90 a gear and rack device within the guide case for causing a compound adjustment of said pin, and a dial for determining the amount of movement of said pin, such movement being determined by markings on said 95 dial.

3. In a coin packaging device, a main frame, an adjustable casing thereon, a movable pin adapted to lie adjacent a stack of coins to be wrapped, and means for moving said pin to and from said stack of coins and transversely of the end of said stack by one movement.

WILLIAM D. HEER.
